[57] CLAIM

The ornamental design for a vehicle steering axle, as shown and described.

DESCRIPTION

FIG. 1 is a perspective view of a vehicle steering axle showing the front, top and one end of our new design; FIG. 2 is a front elevational view thereof; FIG. 3 is a top plan view thereof; FIG. 4 is a rear elevational view thereof; FIG. 5 is a bottom plan view thereof; and, FIG. 6 is an end elevational view of said one end, the opposite end being a mirror image thereof.

FIG. 1
